UNITED STATES PATENT OFFICE.

GEORGE W. ULLMAN, OF NEW YORK, N. Y.

RECEPTACLE FOR PRINTER'S INK.

Application filed February 7, 1922. Serial No. 534,760.

To all whom it may concern:

Be it known that I, GEORGE W. ULLMAN, a citizen of the United States, residing at New York, in the county of New York and State of New York, have invented certain new and useful Improvements in Receptacles for Printer's Ink, of which the following is a full, clear, and exact description.

10 The invention which constitutes the subject matter of this application relates to a receptacle designed primarily for containing printer's ink and other liquids which undergo deterioration as a result of air or 15 other gases confined therein, either accidentally or otherwise.

In the manufacture of receptacles or cans for containing printer's ink it is a well known fact that they vary in volume which 20 is due, at least in a large measure, to the material and methods adopted in their construction. Hence when a certain quantity, either by weight or volume, is placed in a particular can, it may or may not fill the 25 same to the desired height. Furthermore, printers' inks are usually sold by weight which necessarily vary more or less in specific gravity in consequence of which a given amount by weight of different kinds of 30 inks will vary in volume with a result that the containers of a given size in which they are placed may or may not be filled, thus leaving an air space therein which causes deterioration, that is a scum forms on the 35 surface thereof thus necessitating the insertion of a paper or similar disk to avoid the formation of such scum. This method of packing the ink in the receptacles has been found to be objectionable because in handling the receptacles after they have been 40 thus packed this paper disk not infrequently sinks into the body of the fluid, thereby preventing them from functioning as they should. Furthermore, in hermetically sealing 45 the closure according to the practice heretofore in vogue other paper or similar sealing material is interposed between the closure and the body of the receptacle, thus rendering the closure extremely different to 50 remove and practically impossible of removal without destroying the closure from thereafter serving as a sealing means.

It is the object of my invention to do away with the difficulties and objections 55 above noted and this I accomplish by constructing the receptacle with a removable

closure for the lower end in filling, and a closure for the upper end in filling, adjustable to the height of the liquid in the receptacle, which closure after adjustment is 60 adapted to be permanently and hermetically sealed, as by crimping or double seaming, to the body of the receptacle, so that what was the upper end in filling becomes the 65 lower end in taking the liquid from the receptacle and vice versa. One of the necessary concomitants of such a device enables the ink to be packed between the upper and lower closures, thus eliminating the air 70 therefrom without the necessity of employing special means for that purpose. Two forms of such a construction is illustrated in the accompanying drawings in which:

Figure 1 is a side view with parts broken away to illustrate the construction of the 75 top and bottom of the receptacle as it comes from the manufacturer, the same having been filled with ink and the filling closure being in position ready for sealing.

Figure 2 is a side view similar to Figure 80 1 with the closure of the filling opening permanently and hermetically sealed to the body of the receptacle. After thus sealed this end of the receptacle becomes the bottom of the same;

Figure 3 is a side view of the receptacle 85 in an inverted position from that shown in Figures 1 and 2; that is to say, in its normal position after it has been filled,

Figures 4 and 5 illustrate another form 90 of the invention in which the crimp or double seam is formed on the exterior of the can, as will be understood.

Referring to the drawing in detail, the reference numeral 10 designates the body of 95 the receptacle, 11, the top of the same in filling and 12 the bottom of the same in filling, the latter being provided with a removable closure 13. After the receptacle is filled through the end 11 the telescoping 100 closure 14 is moved downwardly therein as indicated in Figure 1 until the same contacts with the upper surface of the liquid. Any suitable means to enable the escape of air from above the ink may be provided, but I prefer to employ a suitable vent opening 15 in the closure 14 for that purpose. The closure 14 comprises a horizontal portion 14^a which is adapted normally to rest upon the surface of the liquid, and a cylindrical portion 14^b which projects outwardly from the portion 14^a and is adapted to tele-

scope with and fit snugly the interior of the end 11 of the receptacle 10. It will thus be seen that the closure 14 is in effect adjustable to the height of the liquid in the 5 receptacle 10 by telescoping the same more or less therein. After the receptacle has been filled as indicated in Figure 1, the upper end of the cylindrical portion 14 is permanently and hermetically sealed to the 10 upper end of the receptacle 11, as by crimping or double seaming one to the other, as clearly indicated at 16 in Figure 2. The end 11 now becomes the bottom of the receptacle and the end 12 the top of the receptacle, as 15 clearly indicated in Figure 3, so that when it is desired to remove the ink or any portion of it from the receptacle, it is only necessary to remove the closure 13 by the proper application of a suitable tool, as will be 20 understood.

In Figures 4 and 5 I have illustrated an alternative construction in which the crimping is effected in an outward as distinguished from an inward direction as clearly 25 illustrated at 16^a in Fig. 5.

A number of advantages of my invention I have indicated in some detail above. It may be pointed out that it has certain other advantages, chief of which is that its 30 construction is such that the manufacturing costs are reduced to a minimum, that is all the parts are capable of being manufactured by simple mechanical means. Even the body itself is practically cylindrical the 35 only irregular surface thereon being the flange 17, thus enabling it to be stamped up from a single piece of metal.

The specific constructions of the receptacle herein illustrated and described are the 40 preferred forms of my invention. It is to be expressly understood, however, that I do not limit myself thereto, as many changes may be made in points of detail and other embodiments resorted to without deviating 45 from the true spirit and scope of my invention as defined in the appended claims.

Having thus described the invention, what is claimed is:

1. A metallic receptacle for printer's ink 50 adapted to be filled with ink at one end and from which the ink is adapted to be removed at the other end comprising a cylindrical body portion, a removable closure for the end of said body portion from 55 which the ink is removed, an adjustable closure for the other end provided with a horizontal portion adapted to rest upon the surface of the liquid and also provided with a cylindrical portion fitting snugly within 60 said cylindrical body portion and adjustable with respect thereto to enable the horizontal portion to be moved into contact with the upper surface of the liquid in the container irrespective of its height therein, said cylindrical portion of said closure extending 65

outwardly from the horizontal portion thereof to enable the filling end of the receptacle and the cylindrical end of said closure to be permanently connected and hermetically sealed to each other. 70

2. A metallic receptacle adapted to be filled with printer's ink at one end and from which the ink is adapted to be removed at the other end comprising a body portion, a removable closure for the end of said body portion from which the ink is removed, and a closure for the filling end provided with a cylindrical portion fitting snugly within said body portion and adjustable with respect thereto to enable the closure to be moved 75 into contact with the upper surface of the liquid in the container irrespective of its height therein, said filling closure provided with means to enable it to be permanently connected and hermetically sealed to 80 the body portion.

3. A metallic receptacle adapted to be filled with printer's ink at one end and from which the ink is adapted to be removed at the other end, comprising a body portion, a removable closure for the end of said body portion from which the ink is removed, a closure for the other end fitting snugly within said body portion and adjustable with respect thereto to enable it to be moved 95 into contact with the upper surface of the liquid in the container irrespective of its height therein, said second closure provided with means to enable it to be permanently connected and hermetically sealed to the 100 body portion, and means for permitting the escape of air from the receptacle in moving said second mentioned closure into contact with the upper surface of the liquid.

4. A metallic receptacle for printer's ink 105 adapted to be filled with ink at one end and from which the ink is adapted to be removed at the other end comprising a cylindrical body portion, a removable closure for the end of said body portion from which the 110 ink is removed provided with a depressed cylindrical portion fitting snugly the interior wall of said cylindrical body portion, an adjustable closure for the other end provided with a horizontal portion adapted 115 to rest upon the surface of the liquid and also provided with a cylindrical portion fitting snugly within and arranged parallel to the walls of said cylindrical body portion and adjustable with respect thereto to 120 enable the horizontal portion to be moved into contact with the upper surface of the liquid irrespective of its height therein, said cylindrical body portion of said closure extending outwardly for a sufficient distance 125 to enable it to be permanently connected and hermetically sealed to the filling end of the receptacle.

5. A metallic receptacle to be filled with printer's ink at one end and from which the 130

ink is adapted to be removed at the other end comprising a body portion, a removable closure for the end of said body portion from which the ink is removed, and a closure 5 for the filling end provided with a cylindrical portion telescoping into and snugly fitting the interior wall of said body portion and adjustable with respect to the latter to enable said closure to be moved into contact 10 with the upper surface of the liquid in the

container irrespective of its height therein, said cylindrical portion of the filling closure constituting means to enable said closure to be permanently connected and hermetically sealed to the filling end of said body 15 portion.

In testimony whereof, I have hereunto set my hand this 25 day of January, 1922.

GEORGE W. ULLMAN.
